MECHANISM FOR PARTIALLY FOLDING CONTAINERS

Eacy D. Bennett, Detroit, Mich., assignor to The American Paper Bottle Company, Toledo, Ohio, a corporation of Ohio

Application September 20, 1937, Serial No. 164,776

13 Claims.

(CL. 93—6)

This invention relates to mechanism for partially folding container closures and particularly to a mechanism for effecting the partial closure of the foldable end extensions of tubular paper containers of the type disclosed in Patent No. 2,047,891, granted July 14, 1936 to Henry T. Scott.

The container which comprises the subject matter of the patent above identified is fabricated of relatively stiff paper, is tubular in form and coated exteriorly and interiorly with paraffin or like coating material the purpose of which is to prevent the penetration of moisture to the paper fibers. It is fabricated by a process which involves the preliminary formation of a flat blank divided by score lines into panels, and the subsequent folding of the major panels with respect to each other into a tube of rectangular cross-section, one end of which is closed and the other end open. That portion of the container adjacent its open end comprises a foldable end extension, being divided by score lines into a number of panels which may be folded relatively to each other, after the container has been coated, into the form of the novel container end closure fully described in said patent. The closure of the container may be effected manually after the container has been charged with a liquid or other commodity to be transported and dispensed. Preferably, however, it is closed by automatically operating machines, the complete closure being effected in two stages, i. e., a first or partial closure which is effected by one machine or apparatus and a final closure which is effected by a second machine or apparatus, both such machines or apparatus comprising units of a complete automatic machine for forming containers from blanks, coating them interiorly and exteriorly, charging with liquid or other commodity, and closing and sealing the same.

It is desirable to effect the closure of the foldable end extension of the container in two stages, instead of in a single stage, by reason of the fact that it is necessary, in order that the several panels of the end extension be folded along score lines with rapidity and accuracy, that the side walls of the container be interiorly supported by a container entering means or mandrel while the end panels are being deflected, thus ensuring that the panels are relatively folded or deflected precisely along the intermediate score lines and not elsewhere. As it is not desirable to insert any side wall supporting mandrel or the like into the container after it has been charged, especially

when the container is to be used in the storage, transportation and dispensing of milk or other perishable commodity, it is desirable that a partial folding of the foldable end extension be effected while the container is empty, then to charge the container, and to finally complete the folding and sealing operation.

A mechanism for partially folding containers of this type is disclosed in Patent 2,056,330 granted to Henry T. Scott October 6, 1936 and it is the primary purpose of the present invention to provide an improved mechanism of the general type disclosed in that patent for effecting the partial closing of the container end extension while the container is empty, a mechanism constructed in accordance with the present invention having a number of practical advantages in operation over that previously used and patented for this purpose. Thus the mechanism of the instant application is lighter, simpler, more compact and somewhat more efficient in operation than that previously made use of, is less likely to require adjustment or replacement of parts due to wear, as the result of long continued operation, and is so designed and constructed that the possibility of the soiling or contamination of the interior of a container upon which it acts is eliminated. The various novel features of the invention will be hereinafter fully described and particularly pointed out, but it will be appreciated by those skilled in the art that that form of the invention which is fully disclosed by way of example may be modified in minor respects without departure from the teachings of the invention.

In the accompanying drawings:

Figure 1 is a partial transverse section through the complete automatic machine of which the present invention comprises one unit, the various operating parts of the novel partial folding mechanism being shown in side elevation;

Figure 2 is a section on line 2—2 of Figure 1, certain of the parts of the machine, however, being shown in elevation, and also in positions which are different from those in which they are illustrated in Figure 1;

Figure 3 is a similar view but showing the operating parts of the mechanism in positions which are different from those in which they are shown to occupy in Figure 2;

Figure 4 is a top plan view of portions of the machine and novel mechanism;

Figure 5 is a section on line 5—5 of Figure 2;

Figure 6 is a section on line 6—6 of Figure 2;

Figure 7 is a perspective view indicating the

position of one of the folding fingers of the mechanism with respect to a container being folded, at the end of the operative stroke of the folding finger;

5 Figure 8 is a front elevation of the operating cam by which the several parts of the mechanism are driven;

Figure 9 is a section on line 9—9 of Figure 3; Figure 10 is a development of the cam, showing 10 the configuration of the cam paths;

Figures 11 and 12 are elevations of two of the container engaging and folding fingers respectively;

15 Figure 13 is a view of a container showing the container in the condition in which it is subjected to the action of the partial folding mechanism; and

18 Figure 14 is a perspective view of the container showing its condition after having been acted 20 upon by the novel partial folding mechanism.

The novel partial folding mechanism is primarily intended for use in the partial folding of containers fabricated of relatively stiff paper and which, after having been coated with a leak-proofing substance, and thereby rendered waterproof, will be self-supporting and shape retaining even when filled with a liquid. The partially completed containers, when ready for submission to the action of the mechanism now to be described, are in the condition illustrated in Figure 13, in which figure the body of the container, which comprises four side walls and bottom (not illustrated) is indicated at B and the foldable end extension thereof is generally indicated at C, 25 the several side panels of the body portion being divided from the end extension by four score lines, disposed in a plane, two of which score lines are indicated in Figure 13 by the reference numerals 10 and 11 respectively. The end extension, above the score lines 10 and 11, may be said to comprise the foldable walls 12 and the collapsible walls 13, the foldable walls 12 being divided by score lines 14 and 15 into three panels, indicated at 16, 17 and 18, the last mentioned panel 30 being a projecting tongue or flap, and the collapsible walls 13 of the end extension being divided by means of diagonal score lines 19 and 20 into three triangular panel sections 21, 22 and 23 and by the substantially horizontal score lines 40 24 and 25, and the intermediate vertical score line 26, into the upper substantially rectangular panels 27 and 28. It is the function of the present apparatus to effect the partial collapse of the collapsible side walls 13 of the end extension 45 by relatively folding the triangular panels 21, 22 and 23 along the diagonal score lines 19 and 20 and relatively folding the substantially rectangular panels 27 and 28 about the vertical score line 26, also to effect the bodily inward deflection 50 or bending, to a certain extent, of the opposed sections 12 of the container end extension about score lines 10, without, however, relatively folding the panels 16, 17 and 18 about score lines 14 and 15, so that the container, after it has been 55 acted upon, has the appearance of that illustrated in Figure 14 and is ready for charging and then final closure and sealing.

The apparatus preferably includes, in addition to the mechanism for folding the panels in the manner just described, a conveyor for automatically bringing containers successively into position to be engaged and operated on and for successively removing the containers after such operation has been performed. The details of 70 75 the conveyor mechanism, however, form no por-

tion of the present invention, and may be modified as desired. The conveyor means, portion of which is shown in the drawings, and which is of the intermittently operating type to effect a step-by-step movement of the containers, is eminently satisfactory for the purpose intended. The conveyor chain is generally indicated at 30 and includes links 31 and cross members 32, upon the ends of which are mounted rollers 33 which run in grooves formed in the parallel rails 34. 10 Mounted upon the chain are equidistantly spaced upstanding members 35 each of which is provided with two container engaging elements 36 adapted to engage the opposite side walls of a container 37, illustrated in chain lines in the various figures. 15 The bottoms of the container may rest upon or at least be guided by the upper edges of the conveyor rails 34 and it will be seen that the container engaging elements 36 engage the container side walls only a short distance above the 20 bottom thereof. The elements 36 are so spaced apart that the container walls are tightly engaged thereby and to a minor extent inwardly deflected, in order that the container may not be upwardly displaced or lifted from the conveyor by the 25 mechanism, now to be described, for partially collapsing its foldable end.

This mechanism is supported upon a frame 40 which is in turn rigidly secured to a base or support 41 which may conveniently be one of the 30 side frame members of the automatic machine of which the mechanism preferably comprises one operating unit. The protective housing 42, likewise mounted upon the frame, and preferably in such manner that it may be readily removed, 35 envelopes the mechanism to a substantial extent. Parallel horizontally extending brackets 43 and 44, which may be said to comprise portions of the frame 40, extend toward a vertical plane which includes the horizontal longitudinal axis 40 of the conveyor chain 30, the outer end of bracket 43 being intersected by such plane while the outer end of bracket 44 terminates short of the plane described. Parallel vertically disposed guide rods are indicated at G and G', each of these rods 45 having its upper end rigidly secured to bracket 43 and its lower end rigidly mounted in bracket 44.

Upon these guide rods are mounted for vertical sliding movement slides 45 and 46, respectively, slide 45 carrying a roller 47 which projects into a cam groove 48 formed in a cam 49 which is circular in plan, and slide 46 carrying a roller 50 projecting into the lower cam groove 51 of cam 49. From an inspection of Figures 8 and 10 the shapes of the cam grooves 48 and 51 may 55 be readily perceived, each of these grooves being continuous and the cam 49 being mounted for rotation about a vertical axis, from which axis all portions of each cam groove are equidistantly spaced. Thus cam 49 is mounted upon a shaft 60 52 the upper end of which is supported in a bearing, portion of which is indicated at 53 and which is rigid with frame 40, the lower end of shaft 52 being rotatably supported in a bearing 54 rigid with bracket 44. Below bearing 54 shaft 65 52 has fixed thereon a spirally toothed gear 55, the teeth of which mesh with those of a similarly formed gear 56 fixed upon horizontally extending shaft 57, which constitutes a drive shaft by means from which the power necessary for 70 the operation is derived. It will be readily perceived that rotation of shaft 57 results in rotation of cam 49 and that, as a result of rotation of the cam, the slides 45 and 46 will be vertically reciprocated along guide rods G and G'. 75

The cam grooves 48 and 51 are so formed that, for the most part, the slides 45 and 46 rise and fall together but are modified to effect relative movements of these slides throughout a certain portion of the angular travel of the cam, as will be hereinafter more fully explained. Various instrumentalities for directly acting upon successive containers are carried by the slides and will now be described.

10 Each container to be acted upon is positioned as indicated in Figures 1, 2 and 3, with the foldable sides 16 disposed in planes parallel to the vertical plane of the conveyor chain and its collapsible sides 13 disposed transversely thereto. 15 The axis of the container is coincident with the axis of the container entering mandrel, generally indicated at M, which mandrel is of such size that it may be freely introduced into the interior of the container. The axis of the container is 20 also positioned equidistantly from the axes of rotation of the pivotally mounted folding fingers which act upon the exterior surfaces of the collapsible sides of the container and extension.

The mandrel M includes container wall supporting fingers 60, each having an elongated container wall engaging edge 61, as shown in Figure 11, and the wall engaging fingers being mounted for rocking movement about parallel supporting studs or arbors 62, the ends of which 30 studs or arbors are rigidly mounted in parallel substantially vertically disposed webs 63 depending from a hollow tubular member 64 which comprises the mandrel support. Each finger 60 is provided with an enlarged toothed portion 60' 35 and the teeth of each such portion are in constant mesh with the teeth of the double rack member 65, comprising the lower end portion of the vertically disposed rod 66 which projects through the tube 64 and is axially movable relatively thereto. It will be seen that, when upward movement of rod 66 is brought about, when the container wall supporting fingers 60 are positioned as shown in Figure 2, that the fingers 60 will be angularly rocked from the positions in 40 which they are shown in this figure to the positions in which they are shown in Figure 3, in which positions their outer edges 61 engage opposed inner wall surfaces of the container and when the rod 66 is moved in the reverse direction fingers 60 will be retracted.

50 The exterior or folding fingers are indicated at 70 and these fingers are likewise mounted for rocking movement about parallel axes, being mounted upon spindles or arbors 71, the ends of which are mounted in spaced supports 72 which comprise integral downward extensions of vertically extending portions 73 of a block or yoke member generally indicated at 74. The lower end of each folding finger 70 has an enlarged circular toothed portion 70' the teeth of which mesh with those of a vertically disposed rack 75 mounted for vertical sliding movement in yoke 74. It is clear that, when the folding fingers 70 are in the positions in which they are shown in Figure 2, and the racks 75 are simultaneously raised through a predetermined distance, the folding fingers will be simultaneously inwardly rocked to the positions in which they are shown in Figure 3, and when the racks are simultaneously lowered the folding fingers will be returned to their original positions, as shown in Figure 2.

Each of the folding fingers 70 is substantially triangular in shape, as indicated in Figure 12, 75 and the upwardly converging edges 78 thereof are

adapted to substantially register, when the finger is rocked inwardly, with the diagonal score lines 19 and 20 of the adjacent collapsible side of the container end extension, folding fingers 70 being adapted to bear against triangular panel 21 over substantially the entire area of the panel during the collapsing operation in order to rock this panel as an entirety about the score line 11 and deflect it into the position in which it is shown in Figure 14. Each folding finger 70 has formed integrally therewith a tapered end extension 80, the sides of which are disposed in planes which intersect at a corner or edge 81 which lies in a plane normal to the axis of rotation of the folding finger. This edge 81 of the extension 80 is disposed at an angle to the flat inner container engaging surface of the folding finger 70 and is adapted to substantially register, when the folding finger is moved toward the container wall, but at a time subsequent to contact of the triangular surface of the folding finger with the face of panel 21, with the vertical rectilinear score line 26, intermediate the panels 27 and 28 of the collapsible container end extension. Thus the projection 80 of the folding finger is intended to, and does, apply in a precise manner a force to the container wall tending to bend the same sharply along score line 26, contact being made after the triangular panel 21 has been slightly deflected from the vertical, and as a result the container wall is sharply folded along this vertical score line, as well as along diagonal score lines 19 and 20 when the folding finger is operated, the integrity of all panels being maintained during the folding operation and sharpness and regularity of folding about the desired score lines realized. In Figure 7 of the drawings the folding fingers 70 are illustrated in the positions which they occupy with respect to the container being acted upon at or about the end of their operating strokes.

During the time that folding fingers 70 are active in effecting the folding operations just described, the edges 61 of the supporting fingers 60 are in contact with the inner faces of the opposed side walls of the container body, each edge 61 being located approximately at or just below a score line 11. Hence the inward movement of folding finger 70 cannot result in inward flexure of the upward portion of the side wall panel below score line 11 but on the other hand a sharp angle is formed between this side wall panel and the triangular panel 21 just above it as the result of the mutual cooperation of the folding fingers 60 and 70. It will be appreciated that as the sides 13 of the foldable end extension are collapsed in the manner just described, the foldable sides 12 will be brought together to a substantial extent, being deflected respectively about the score lines 10 as hinge lines, the container as thus modified being shown in Figure 14.

The folding and supporting fingers must of course be raised and lowered and accurately actuated in timed relationship. Both sets of operating fingers simultaneously rise and fall with the yoke 74 and yoke 74 is caused to reciprocate vertically in timed relationship to the movements of the conveyor chain. Yoke 74 is secured to the outer end of bracket 46 integral with slide 46, which slide is vertically moved due to the engagement of roller 50 in slot 51 of the rotating cam 49. The tubular member 64 upon the lower end of which the container entering collapsible mandrel M is mounted has an enlarged upper portion which extends through an aperture formed in

yoke 74, being secured in any desired position with respect to the main portion of the yoke by the clamping blocks 85 and 86 which are retained within a transverse recess in the yoke 74 and drawn into tight engagement with the enlarged tubular portion 64 by means of screw 87. The upper end of member 64 is hollowed out axially to receive a coiled compression spring 88 the upper end of this spring being confined by cap 89 and its lower end resting against an abutment 90 adjustably secured to the central rod 66. Spring 88 is normally in compression and, when released, thrusts rod 66 downwardly with respect to the yoke and hence causes inward tilting of the supporting fingers 60 to the positions in which they are shown in Figure 2. The upper end of rod 66 passes through an aperture in the end of bracket 43 and there are mounted thereon, at a point above this last mentioned bracket, two adjustable nuts, an abutment nut 92 and lock nut 92'. The position of the nuts 92 and 93 may be regulated at will to determine the exact instant, in the downward travel of the yoke 74, of stoppage of rod 66 and hence, assuming that there is continued downward movement of the yoke and hence relative movement between the yoke and rod 66, bringing about the actuation or spreading out of the supporting fingers at a very definite point in the travel of rod 66, which point is so regulated that the fingers 60, when extended, contact with the container walls at or just below score lines 11. As the yoke is raised, the cap 88 is of course elevated, allowing the spring 88 to expand, yet maintaining sufficient downward pressure on spring abutment 90 to prevent, for an initial period during the rising movement of the yoke, raising of the rod 66, and hence ensuring relative movement of the rod and yoke and inward folding of the supporting finger 60. After this relative movement has occurred, and the supporting fingers 60 have been moved into the positions in which they have been shown in Figure 2, the yoke and rod will thereafter move upwardly in unison as the slide 45 is raised and no outswinging of the supporting fingers 60 will again occur until, upon the subsequent downward movement of the yoke, the abutment nut 92 again comes in contact with bracket 43.

In order to effect swinging movement of the folding fingers 70 in timed relationship with the movements of other parts of the mechanism, each of these fingers is operatively connected to the upper slide 45. Thus slide 45 has an extension 45' provided with spaced vertical apertures 45² through which the threaded upwardly projecting stems 93 of racks 94 extend the connection between bracket or slide extension 45' and racks 94 being a lost motion connection, the position of nuts 95 and 96 on stems 93 determining the amount of lost motion. Intermediate the upper and lower nuts 96 are spring abutments in the nature of washers, indicated at 97, and coil springs 98 have their upper ends resting against these spring abutments and their lower ends resting upon the yoke 74 encircling the semi-circular racks 94. It will be perceived that racks 94 are guided in their vertical movements in bushings 99 each of which is cut away in the vicinity of a pinion 100 mounted for rotation about an axis fixed with respect to yoke 74, pinion 100 meshing with the teeth of both racks 94 and 75 so that upward movement of rack 94 will effect downward movement of rack 75 and vice versa.

When the yoke 74 is in its elevated or inoperative position, the springs 98 are expanded, as

shown in Figure 2, the racks 94 are in their uppermost positions, the racks 75 in their lowermost positions, and folding fingers 70 in inoperative position. The rod 66 has also been thrust downwardly by the action of spring 88 so that the supporting fingers 60 are also in inoperative position. The abutment nuts 92 and 92' on the upper end of rod 66 are elevated a substantial distance above the bracket 43 and it is while the parts are in the positions just described that the conveyor chain functions to bring a container into position to be engaged and partially folded. At this time the rollers 47 and 50 of the upper and lower slides are in the horizontal portions 48² and 51² of the cam slots 48 and 51 respectively. As the cam 49 rotates, however, these rollers will enter the downwardly inclined portions 48² and 51² of the cam slots, which inclined portions are of substantially identical slope with respect to the horizontal and therefore bring about simultaneous and equal downward movements of the slides 45 and 46 which slides carry the slide extension 45', and the yoke 74, respectively. The roller 50 then enters the horizontal mid portion 51³ of the cam slot 51 and the downward movement of yoke 74 immediately ceases, the folding fingers mounted on this slide having reached operative position. Just prior, however, to the time when yoke 74 reaches its lowermost position, the abutment nut 92 comes into contact with the upper surface of bracket 43 halting the downward movement of rod 66 while the downward movement of the yoke still continues to a limited extent. A slight relative movement of rod and yoke therefore has occurred before the yoke 74 is finally positioned, this relative movement being sufficient to extend the supporting fingers 60 or to move them into the positions in which they are shown in Figure 3 so that the edges 61 of the supporting fingers engage opposed inner wall surfaces of the container at the instant when the downward movement of yoke 74 ceases.

The upper slide 45, however, continues to move downwardly after the movement of yoke 74 is halted, due to the fact that cam slot 48² continues to slope downwardly to a point of sharp reverse, having no horizontal portion such as that indicated at 51³ in Figure 10. As a result of this continued downward movement of the upper slide 45, the racks 94 are thrust downwardly against the actions of springs 98, the racks 75 being simultaneously drawn upwardly and the folding fingers 70 swung inwardly to the positions shown in Figure 3, folding the collapsible sides of the container. After the cam 49 has travelled a further distance, and the rollers 47 and 50 have passed the vertical mid-line 102 of the cam, the upper roller 47 will commence its upward or return movement while the lower roller 50 still remains in the horizontal portion 51³ of its cam slot. Hence the slide extension bracket 45' will rise while yoke 74 still remains stationary, permitting racks 94 to be elevated by springs 98 and thereby causing downward movement of racks 75 and retraction of folding fingers 70. Shortly thereafter the yoke 74 will likewise begin its upward movement and simultaneously with such initial upward movement the folding fingers 60 are retracted since, owing to the expanding action of spring 88, rod 66 is held in its lowermost position until the yoke has travelled an appreciable distance upwardly and the spring abutment 90 has seated itself against the lower end of the spring recess, as shown in Fig-

ure 2. At this point the supporting fingers 60 have been completely retracted and the fingers and other parts which together comprise the collapsible container entering mandrel may be 5 readily withdrawn from the sharply folded container. The cycle of operations is repeated for subsequently positioned containers and, as has previously been pointed out, the movements of the folding mechanism are synchronized with 10 those of the conveyor carrier.

Attached to the side of the yoke member 74 is a member 110 comprising essentially two downwardly and outwardly inclined wings 111 which make equal angles with a vertical plane through 15 the axis of the vertical conveyor chain. As the yoke 74 is lowered, the wings of member 110 contact with the sloping sides 12 of a container just below it and which container has just been previously partially folded by the folding mechanism. The pressure of the wings 111 upon the sides is sufficiently great to more sharply define 20 the angles between the sloping sides 12 and the vertical sides of the container body just below score lines 10, which is of advantage in the subsequent closure of the container.

To the lower end of the mandrel M is secured a dirt catching and retaining pan 115 to catch and retain any dirt, metal fragments or oil which may fall from the operating parts. The pan 30 115, therefore, serves to prevent accidental soiling or contamination of a container, which of course is highly undesirable when food products are being handled.

Having thus described the invention, what is 35 claimed as new and desired to be secured by Letters Patent is:

1. Mechanism for partially folding container closures comprising, a folding finger adapted to be moved toward a container supported in a predetermined position, to inwardly fold or deflect portion of such container, and thereafter to be moved away from such container, and mechanism for operating said finger including two relatively movable members, an element carried by 40 one of said members and also movable with respect thereto, said element being operatively connected to said folding finger and to the other member, whereby relative movement of said members results in movement of said finger.

50 2. Mechanism for partially folding container closures comprising, a folding finger adapted to be moved toward a container supported in a predetermined position to inwardly fold a portion of said container and to be thereafter moved away from such container, and mechanism for operating said finger including two relatively movable members, an element carried by one of said members and also movable with respect thereto, a second element carried by said member 55 and movable with respect thereto, the first element being operatively connected to said folding finger and the second element to said other member, and means operatively connecting said elements whereby relative movement of said members results in movement of said finger.

65 3. Mechanism for partially folding container closures comprising, a folding finger adapted to be moved toward a container supported in a predetermined position to inwardly fold a portion of said container and to be thereafter moved away from such container, and mechanism for operating said finger including two relatively movable members, a rack carried by one of said members and longitudinally slidably with respect thereto, a second rack slidably carried by said mem-

ber, a pinion rotatably mounted on said member with which pinion both racks mesh, means operatively connecting one rack to the folding finger and second means operatively connecting the other rack to the other member, whereby relative movement of said members causes simultaneous movements of the racks in opposite directions and movement of said finger.

4. Mechanism for partially folding container closures comprising, a folding finger adapted to be moved toward a container supported in a predetermined position to inwardly fold a portion of said container and to be thereafter moved away from such container, and mechanism for operating said finger including two relatively movable members, a rack carried by one of said members and longitudinally slidably with respect thereto, a second rack slidably carried by said member, a pinion rotatably mounted on said member with which pinion both racks mesh, means operatively connecting one rack to the folding finger and second means including a lost motion device operatively connecting the other rack to the other member, whereby relative movement of said members results in delayed movement 25 of said finger.

5. The combination set forth in claim 4 in which the said racks are disposed in parallel relationship and said pinion is mounted for rotation about an axis fixed with respect to said member.

6. The combination set forth in claim 4 in which yielding means acts on one of said racks at all times and tends to produce movement of said rack in such direction that retraction of the folding finger results.

7. Mechanism for partially folding container closures including a container entering mandrel which comprises a supporting member, container wall engaging fingers movably mounted on 40 said member, an element for simultaneously acting upon, and operating, said fingers, and a spring for normally urging said element in such direction as to cause retraction of said fingers.

8. The combination set forth in claim 7 in 45 which the spring is housed within a recess in the supporting member at a point remote from the container wall engaging members.

9. Mechanism for partially folding container closures including a container entering mandrel 50 comprising a vertically disposed supporting member, container wall engaging fingers movably mounted upon the said member at the lower end thereof, and dirt catching and retaining pan attached to said member and underlying said members.

10. Mechanism for partially folding container closures including a container entering mandrel comprising a vertically disposed supporting member, container wall engaging fingers pivotally connected to the lower end of said member, a vertically disposed operating rod the lower end of which is operatively connected to said fingers, and a dirt retaining pan underlying said rod and the pivotal connections between said member and 60 fingers.

11. In a mechanism for partially folding the foldable end closures of scored paper containers comprising a conveyor for holding containers and advancing the same along a predetermined path 70 with a step-by-step motion, means for acting upon and partially folding a container while temporarily positioned at one point in its travel, and a device carried by said means, and movable therewith, for acting upon said container at a 75

subsequent point in its travel to deflect the previously folded panels thereof.

12. In a mechanism for partially folding the foldable end closures of scored paper containers comprising a conveyor for holding containers and advancing the same along a predetermined path with a step-by-step motion, means movable vertically with respect to the conveyor for engaging and partially folding a container end while temporarily halted at one point in the travel thereof, and a device secured to said means and vertically movable therewith for inwardly deflecting two opposed previously folded panels of said container while the container is at rest at a point next following that which it occupies when

being partially folded, said device including two panel engaging elements angularly fixed with respect to each other.

13. Mechanism for relatively folding the triangular and substantially rectangular panels of the scored side walls of a paper container comprising, a triangular folding finger adapted to engage a triangular panel over substantially the entire area thereof, and a part to engage a scored portion intermediate two adjacent panels, said part projecting from the apex of the folding finger and having an edge inclined to the plane of said finger and flat side faces meeting at said edge.

RACY D. BENNETT.

15
